Attorney.

UNITED STATES PATENT OFFICE.

URIAH O. LONG, OF LOS ANGELES, CALIFORNIA.

RAILWAY-TIE.

1,366,673.

Specification of Letters Patent. Patented Jan. 25, 1921.

Application filed November 24, 1919. Serial No. 340,273.

To all whom it may concern:

Be it known that I, URIAH O. LONG, a citizen of the United States, residing at 5419 Marmion Way, city of Los Angeles, in the county of Los Angeles, and State of California, have invented certain new and useful Improvements in Railway-Ties, of which the following is a specification.

My invention relates to a railway tie and particularly to improvements in the device of Letters Patent of the United States, Number 1,306,014, issued to me under date of June 10, 1919.

Specifically I aim to provide effective means to prevent corrosion or oxidation of the parts within the pockets receiving the rail-fastening means; a tie of a particular shape to save material and facilitate handling; a tie having improved reinforcing means in a composite body, and one otherwise improved as will later appear and be claimed.

In the accompanying drawings illustrating one preferred embodiment:—

Figure 1 is a side elevation of the improved tie with track rails secured thereto and in cross-section;

Fig. 2 is a fragmentary longitudinal sectional view on an enlarged scale;

Fig. 3 is a cross sectional view on the line 3—3 of Fig. 2;

Fig. 4 is a fragmentary plan view of the tie partly broken away;

Fig. 5 is a detail perspective view of the rail fastening or spike which may be used; and

Fig. 6 is an enlarged view in longitudinal section of the metallic parts only of one side of the tie and of a modified form of rail fastening.

Referring particularly to the drawings, the tie 10 may be molded or formed from any suitable composite material, usually concrete. The sides and ends of the tie may be beveled or inclined as at 11 to effect a saving of material and the edges may be rounded at the junctions of the walls. The tie is longest and widest at the base or bottom and is preferably enlarged as at 12 to be reinforced where the rails are supported. Pockets facilitating handling may be provided at 13 in Figs. 1 and 3. The bottom of the tie is centrally cut away to provide any desired shape of wall 14 which

will grip the ground to reduce chances of lateral movement and the weight of the tie.

Composite body 10 is preferably reinforced by a suitable skeleton structure, preferably of metal. Suitable transverse rods 15 are used and their ends 15' are hooked or bent to facilitate anchoring. Links 16 are also embedded in the composite body, being positioned by the rods 14 while endless rods or wires 17 are fastened around the rods 14 and rods or wires 18 are passed alternately over the upper and lower rod 14 of each pair. It will be noted that the outermost links 16, in this instance, are preferably inclined, to conform with the shape of the end of the tie, as shown in Fig. 2. The various rods and wires may be tied in proper relation by thin wires before being embedded in the concrete or other composite body, in the course of manufacture.

Beneath each rail, the tie is further reinforced by a horizontally disposed endless rod 20. In addition, an elongated brace plate or bar is embedded in the tie having a horizontal portion 21, an inclined end portion 22 and inclined portions 23, one substantially following the angle of the portions of rod 14. Parallel with portion 21 is a plate 24 and disposed between the portion 21 and plate 24 are a plurality of U-shaped bars. These bars have upstanding portions 25 and feet or lugs 26 which bear against the plate 24 and a reinforcing plate 27 resting on the portion 21. Bolts or rivets 28 pass through lugs 26 and plates 24 at the top and lugs 26, plate 27 and portion 21 at the bottom. The top bolts or rivets 28 also pass through lugs 29 of strut bars 30 joined to the portions 22 and 23 by lugs 31 of the strut bars and bolts or rivets 32. It will be noticed that the strut bars 30 also have vertical portions 30' which serve to lower the main portions of the strut bars in order to receive a considerable quantity of concrete above it or in other words to be embedded at a greater depth. Plates 27, if desired, may be omitted but their use is advisable since they afford additional strength. Also, a wear plate 33, which rests on plate 24, may be dispensed with if desired. Metallic side plates 34 are disposed beneath portion 24, resting on plate 27 and on the interior face bearing against the sides of portion 25 and lugs 26 being clamped in place by means

of bolts 35. Plates 34 preferably have laterally extending flanges or lugs 36 (Fig. 3) through which said rivets 28 pass. In plates 34, openings 37 may be provided to enable 5 insertion of the composite material.

A pair of the U-shaped bars is disposed on each side of each track rail 38 and the upstanding walls 25 of each pair are spaced from each other to provide pockets 39 with 10 which openings 40 in plates 24 and 33 register. A rail fastening member or spike 41 may pass through said openings 40 and into each pocket 39, into binding and wedging relation with retainers or keys 42, prefer- 15 ably of softer metal than the spikes, for instance soft steel as distinguished from lead, which is referred to in my Patent 1,306,014. At the continuous edges, the spikes and keys may have suitable interengaging corruga- 20 tions or projections 43. The pockets are preferably wider at their bases than at their tops as shown in Fig. 6, to facilitate expansion of the keys and provide substantially dove-tailed connections between the spikes 25 and pockets. Spikes 41 may have heads 41' as in Figs. 1, 2 and 3, to overlap the base flanges of the rails.

A very important feature of my present 30 improvements resides in a means to seal the pockets against the entrance of moisture so that the spike parts therein cannot injuriously corrode or unduly oxidize. The spike therefore, as shown in Fig. 5, in detail may have a continuous groove around it at 50 35 adapted to register, when the spike is in place, with a groove 52 extending endlessly in plate 24 at opening 40. Openings 40 of plate 33 are enlarged or beveled downwardly as shown at 40' so that a sealing medium 40 may be poured therethrough to enter grooves 50 and 52. This medium may be molten metal like lead or babbitt, which will harden and seal the pockets against the entrance of moisture. Also the spike parts within the 45 pockets may be coated with asphaltum or other corrosion-preventing medium before insertion into the pockets and the sealing thereof.

As in the case of the device of my Patent

1,306,014, a limitation to the form of fastening means used is not to be implied since modifications may be resorted to as in Fig. 6. In this figure, a flange engaging bar 44 and fish plate 45 are formed integral with plate 33 and usual fastening bolt means 47 are 55 passed through the rail and fish plates and filler members 48 and 49.

In manufacturing, the steps outlined in my patent referred to are followed, after which, the sealing medium 53 is applied, pre-supposing coating of the spikes with the asphaltum prior thereto.

As merely the preferred embodiment has been illustrated and described, it is to be understood that changes in the details of 65 construction may be resorted to within the spirit and scope of my invention.

I claim:

1. A rail tie having a pocket, rail securing means extending into the pocket, and means 70 overlapping both the pocket and said means to seal the pocket for the purpose specified.

2. A rail tie having a pocket, rail securing means extending into the pocket, said means having a groove, and means extending into 75 the groove to seal the pocket for the purpose specified.

3. A rail tie having a pocket, rail securing means extending into the pocket, said pocket and means each having a groove, and means 80 extending into said grooves to seal the pocket for the purpose specified.

4. A rail tie having a pocket means, rail securing means extending therewith, one of said means having a groove, sealing means 85 for the pocket means, said sealing means extending into said groove and engaging one of the first mentioned means to seal the pocket for the purpose specified.

5. A rail tie having a pocket means, a rail fastening member extending therewith, said pocket means having a groove, said member having a groove, a plate over said pocket member, and a pouring means in said plate 90 for molten metal to enter said groove to seal the pocket for the purpose specified.

In testimony whereof I affix my signature.
URIAH O. LONG.
